GLUE APPLICATOR

Cyril W. Hollar, Hickory, N. C.

Application July 7, 1950, Serial No. 172,589

5 Claims. (Cl. 118—222)

1

This invention relates to an improved glue applicator of the rotary disc type, the primary object of the invention being to provide a simpler, more efficient, and more versatile device of this kind wherein two applicator discs are involved which can be adjusted axially with respect to each other in order to apply the glue to narrow and to wider work, together with adjustable guide means for guiding the work in contact with the discs.

Another important object of the invention is to provide a motor driven device of the character indicated above which, aside from the motor which is removable, is in the form of a unit which can be immersed in water when desired and not in use, without harm thereto.

Other important objects and advantageous features of the invention will be apparent from the following description and the accompanying drawings, wherein, for purposes of illustration only, a specific embodiment of the invention is set forth in detail.

In the drawings, wherein like numerals designate like parts throughout the several views:

Figure 1 is a top plan view;

Figure 2 is a vertical longitudinal section taken on the line 2—2 of Figure 4;

Figure 3 is a rear elevation; and

Figure 4 is a transverse vertical section taken on the line 4—4 of Figure 2.

Referring in detail to the drawings, the illustrated glue applicator 5 is adapted for mounting upon a horizontal support 6, such as a work table, in association with a rectangular open top tank or container resting upon the support 6 and containing glue 8, to be applied to such as portions of furniture (not shown) in a furniture factory. Obviously, the applicator is not necessarily limited to applying glue, or to applying glue to furniture pieces but is adaptable to applying other fluids to selected objects.

The applicator 5 comprises a bracket or column 9 comprising a horizontal plate 10 forming a base or foot to rest upon the horizontal support 6, a vertical plate 11 rising from the base 10, and a horizontal plate 12 on the upper end of the plate 11. The horizontal plate 12 includes a relatively small square portion 14 constituting a motor supporting platform, located over the column 9, and a relatively large longitudinally elongated work supporting or table portion 15 extending beyond opposite sides of and in front of the platform 14. The work supporting or table portion 15 has parallel longitudinal rear and front edges 16 and 17, respectively, and is formed with a rectangular

2

opening 18, elongated in the same direction as the table portion 15, and having rear and front edges 19 and 20, respectively, parallelly spaced from the edges 16 and 17 of the table portion 15, as shown in Figure 1, and end edges 21 parallelly spaced from and located outwardly of the sides of the platform 14. The parts 9, 14 and 15 constitute the frame of the device and are preferably made of rust resistant and non-corroding material like Babbitt metal.

A suitable ratioed electric motor 23 has a base 23' resting upon the platform 14 and removably secured thereto by suitable means indicated at 24, with its shaft 25 directed forwardly and provided on its forward end with a bevel pinion 26. The top of the portion 27 of the table portion 15 located immediately between the platform 14 and the rear edge 19 of the opening 18, serves as a supporting surface for the parallelly spaced, transversely elongated and rearwardly extending horizontal feet 28 of the work guide 29, the feet 28 projecting from the lower edge of a vertical, longitudinally elongated work guide plate 30, extending substantially parallel to the rear edge 19 of the opening 18. Studs 31 fixed to the portion 27 rise through longitudinal slots 32 formed in the feet 28 and are provided with wing nuts 33 whereby the guide plate 30 can be secured in adjusted position. The guide 29, studs 31, and wing nuts 33 are preferably of brass or of other rust and corrosion resisting metal.

At a point midway between the studs 31, a vertical, preferably brass, drive shaft 34 extends through the portion 27 and above and below the table portion 15 and is supportably journaled in a bearing 35 located below the portion 27 and secured to a forward extension 36 on the vertical bracket plate 11, as shown in Figure 4. Preferably brass bevel pinions 37 and 38 are secured on the upper and lower ends, respectively, of the drive shaft 34, the upper pinion 37 being in mesh with the motor shaft pinion 26.

The table portion 15 has parallel rear and front ribs 40 and 41, respectively, projecting on its underside and extending the length thereof, the rear rib 40 being located along the rear edge 19 of the opening 18, and the front rib 41 being located along the front edge 20 of the table portion 15. These ribs serve as stiffening reinforcements for the table portion 15 and can rest removably upon the upper edge 42 of the glue tank or container 7 where the tank or container 7, when in position upon the horizontal support 6, is of sufficient height. Spaced legs 43 depend from the front rib 41 to engage within the tank

or container 7 to eliminate shifting thereof out of position on the support 6.

Relatively narrow, vertically elongated rear and front arms 44 and 45 depend from the ribs 40 and 41, respectively, in transverse alignment with the drive shaft 34, to a level below the lower pinion 38 on the shaft 34, as shown particularly well in Figure 4, to support the horizontal, transversely extending driven shaft 46.

The driven shaft 46 comprises a spindle 47 extending between the arms 44 and 45, having a smooth rear portion 48 extending rearwardly through and journaled in a bearing 46 in the lower part of the rear arm 44, having a fixed bevel pinion 53 thereon in mesh with the pinion 38 on the lower end of the drive shaft 34. A relatively short rear sleeve 51 is circumposed on and secured to the spindle 47 in front of the arm 44 and has circumposed thereon the hub 52 of the rear applicator disc 53 whereby the rear disc 53 occupies a stationary position near the rear edge 49 of the opening 18 in the table portion 15, as shown in Figure 4. A set screw 54 traversing the hub 52 locks the disc 53 in position in the short sleeve 51 and permits some adjustment thereof along the sleeve 51.

The driven shaft 46 further comprises a relatively long front sleeve 55 which is threaded on the threaded front portion 56 of the spindle 47, so as to be adjustable along the spindle 47 in either direction. A lock nut 57 on the front end portion of the threaded spindle portion 56 is provided to be engaged with the front end 58 of the long sleeve 55 to lock the same in adjusted position along the spindle 47. The front end portion of the long sleeve 55 is journaled in and slideable through the cover part of the front arm 45, as indicated at 59. The front applicator disc 60 is similar to the rear applicator disc 53 and has a hub 61 circumposed on the rear end of the long sleeve 55 and secured thereon by a set screw 62. As a consequence, when the sleeve 55 is adjusted along the spindle 47, the front disc 60 is correspondingly adjusted toward or away from the rear disc 53, as may be required to apply to differently spaced areas of a work piece (not shown), glue 8 picked up by the discs from the tank 7, as the driven shaft 46 is rotated by the drive shaft 34, which is in turn driven by the motor 22. A start and stop switch 64 for the motor 22 may be conveniently mounted on one side of the platform 14.

The applicator discs 53 and 60 have oppositely bevelled peripheral applicator surfaces 65 which project through the opening 18 and above the table portion 15, and plane smooth facing surfaces 66 which are engageable, as shown in Figure 4, in the extreme rearward adjustment of the front disc 60. The front disc 60 is adjustable, by the means described above, to occupy a position near the front edge 20 of the opening 18, wherein the front disc 60 is in substantially spaced relation to the rear disc 53, and the peripheral applicator edges or surfaces are spaced to apply glue to relatively widely spaced areas of a work piece. The work pieces are moved along the table portion 15 in contact with the guide plate 30 of the guide 29 as they are engaged with one or both of the peripheral applicator edges 65 of the discs, thereby assuring accurate and uniform application of the glue.

When the device 5 is not in use or it is desired to clean the same of glue or other applicator fluid, the motor 22 can be removed from the platform 14 and the remainder of the device

placed in water or other cleaning fluid without risk of rusting or corroding the same.

What is claimed is:

1. In a fluid applicator, a vertical bracket having a lower end arranged to rest upon a support, a horizontal work-supporting plate mounted on and extending from one side of the bracket at a level above the lower end of the bracket, said plate being formed with a transverse opening, said horizontal plate having vertical arms at opposite sides of said opening and depending therefrom, a transverse shaft journaled in and extending between lower portions of said arms, applicator disc means mounted on said shaft between said arms and rising through said transverse opening, and a fluid container removably mounted on said support at one side of said bracket into which said arms, said shaft, and said applicator disk means depend, said fluid container being otherwise unconnected with said bracket, said plate, said vertical arms, and said shaft.

2. In a fluid applicator, a vertical bracket having a lower end arranged to rest upon a support, a horizontal work-supporting plate mounted on and extending from one side of said bracket at a level above the lower end of the bracket, said plate being formed with a transverse opening, said horizontal plate having vertical arms at opposite sides of said opening and depending therefrom, a transverse shaft journaled in and extending between lower portions of said arms, applicator disc means mounted on said shaft between said arms and rising through said transverse opening, and a fluid container removably mounted on said support at one side of said bracket into which said arms, said shaft, and said applicator disk means depend, said fluid container being otherwise unconnected with said bracket, said plate, said vertical arms, and said shaft, a vertical drive shaft journaled in said horizontal plate and extending therebelow along one of said depending arms, gear means operatively connecting said drive shaft with said transverse shaft, and motor means mounted on the upper part of said bracket and operatively connected to an upper part of said drive shaft.

3. The combination with a fluid container removably mounted on a support of a fluid applicator comprising a vertical bracket removably resting upon said support alongside of said container and unconnected with the container, a horizontal work-supporting plate on and projecting laterally from said bracket over the container at a level above the top of the container, laterally spaced arms depending from said plate into the container, a horizontal shaft journaled in said arms at a level below the top of the container, rotary applicator means on said shaft, said work supporting plate being formed with an opening exposing said applicator means to work supported on said plate, and operating means for turning said applicator means for applying fluid from the container to the work.

4. The combination with a fluid container removably mounted on a support of a fluid applicator comprising a vertical bracket removably resting upon said support alongside of said container and unconnected with the container, a horizontal work supporting plate on and projecting laterally from said bracket over the container at a level above the top of the container, laterally spaced arms depending from said plate into the container, a horizontal shaft journaled in said arms at a level below the top of the container,

rotary applicator means on said shaft, said work supporting plate being formed with an opening exposing said applicator means to work supported on said plate, and operating means for turning said applicator means for applying fluid from the container to the work, said operating means comprising motor means mounted on said bracket and operatively connected to said applicator means.

5. In a fluid applicator, a work supporting plate, laterally spaced arms depending from said plate, a spindle extending between lower portions of said arms, said spindle having a smooth end portion journaled in one of said arms and a threaded end portion, a relatively short receiving and fixed on said smooth end portion and carrying a fixed concentric applicator disk, a relatively long sleeve threaded on said threaded end portion of the spindle, said long sleeve being journaled in the other arm and carrying an other concentric applicator disk, said work supporting plate being formed with an opening extending between said arms and exposing said ap-

plicator disks to work on said plate, said long sleeve being rotatable on said threaded end portion of the spindle in opposite directions so as to adjust said other applicator disk toward and away from said fixed applicator disk, and a lock nut on said threaded end portion of the spindle for engagement with the adjacent end of said long sleeve for locking said other applicator disk in adjusted relation to the fixed applicator disk.
